US0D1089469S

(12) **United States Design Patent** (10) **Patent No.:** **US D1,089,469 S**
(45) **Date of Patent:** **** Aug. 19, 2025**

(54) **LEVERAGE GYM**

(71) Applicant: **DOMINO INTERNATIONAL TRADE INC**, Sheridan, WY (US)

(72) Inventor: **Huihui Liu**, Pizhou (CN)

(73) Assignee: **DOMINO INTERNATIONAL TRADE INC**, Sheridan, WY (US)

(**) Term: **15 Years**

(21) Appl. No.: **29/987,186**

(22) Filed: **Jan. 22, 2025**

(51) LOC (15) Cl. **21-02**

(52) U.S. Cl.

USPC **D21/686**

(58) **Field of Classification Search**
